STACKED COMPARTMENT CONVEYOR ASSEMBLY FOR DISPENSING MACHINE
Le Roy D. Gore, Independence, Mo., assignor to The Vendo Company, Kansas City, Mo., a corporation of Missouri

Filed Aug. 18, 1966, Ser. No. 573,349
17 Claims. (Cl. 312—352)

ABSTRACT OF THE DISCLOSURE

A dispensing machine having a series of product receiving individual compartments positioned in stacked relationship presenting two side-by-side vertical columns with mechanism being provided for raising one stack one step while lowering the other stack one step, and to effect transfer of the uppermost compartment from the stack which has been raised to the top of the other stack after the latter has been lowered and to transfer the lowermost compartment of the stack which has been lowered to the bottom of the stack which has been raised. Rotatable cam structure is provided at the bottom of the stacks for simultaneously supporting both stacks while being operable during rotation thereof to raise the one stack and lower the other stack. The cam structure is located in disposition such that at least a part of the gravitational load of the stack being lowered is transferred as an upward force on the stack being raised, thus minimizing the power required to drive the cam structure. A reciprocable pusher forming a part of the mechanism is operable in timed relationship with the cam structure to shift the upper compartment from the stack which is raised to the stack which is lowered by the cam structure.

The instant invention relates to an improved stacked compartment conveyor assembly of the type having special utility for use in an article dispensing machine and in particular, relates to improved mechanism for supporting and moving the individual compartments of such an assembly along a closed loop path.

Product dispensing machines and related mechanisms, such as, for example, low profile display counters, have heretofore been provided with conveyor mechanism for supporting a plurality of individual product compartments disposed in a pair of side-by-side stacks thereof. In these assemblies, products are made available for dispensing by controlled shifting of the compartments to successively bring the same into alignment with a product delivery area. This arrangement, although somewhat expensive, is desirable from a space conservation viewpoint and additionally provides flexibility for use of the machine with a variety of different articles including pressure deformable articles and products of various sizes. In machines of this type, the compartments of one stack are generally raised, the compartments of the other stack are lowered, the lowermost compartment of the lowered stack is inserted under the raised stack, and the uppermost compartment of the latter is transferred onto the lowered stack.

Machines having stacked compartment conveyor mechanism have generally been motor driven. In the past it has been considered relatively essential that large motors be used for lifting the stack of compartment units particularly when the compartments are fully loaded. These large motors have increased the manufacturing as well as operational expenses of the machines.

It is, therefore, the primary object of the instant invention to provide a stacked unit, closed loop conveyor for such a machine wherein is included structure permitting the use of a smaller motor than has heretofore been pos-

2

sible, whereby manufacture and use of the machine is less expensive.

As a corollary to the foregoing object, it is a very important aim of the present invention to provide an element engageable with the respective stacks for translating the gravitational force exerted by the stack being lowered into an upwardly directed force acting on the stack being raised, thereby permitting use of a smaller motor.

A very important object of the invention is to provide means for rotatably mounting such an element for rotation about an axis disposed between the stacks whereby the stack being raised is supported by an upwardly moving portion of the element disposed on one side of the axis, and the stack being lowered is supported by a downwardly moving portion of the element disposed on the other side of the axis and the element mounting means provides a fulcrum for translating the gravitational force exerted on the downwardly moving portion by the descending stack into an upwardly directed force exerted on the ascending stack through the upwardly moving portion of the element.

Another very important object of the instant invention is the provision of novel support and release means for said stacks including a movable element having a surface engageable with the stacks for supporting the same while the lowermost compartment of the lowered stack is released for gravitation and transfer of the same beneath the ascending stack and a second surface disposed for shifting the released unit laterally and upwardly toward the ascending stack upon further movement of the element, to the end that the individual units of the stacks are efficiently lowered, transferred and raised by use of novel conveyor apparatus requiring a minimum number of individual components and separate operations.

A further important object of the present invention is to provide mechanism for operating the conveyor including a releasable latch disposed for engaging the descending stack and a pair of cam elements mounted on opposite sides of the stacks for rotation about an axis extending between the stacks and having continuous cam tracks including an arcuate surface movable into stack-supporting disposition during release of the lowermost unit and a flat surface for transferring the released unit and then simultaneously raising and lowering the respective stacks, whereby the gravitational force exerted on the element by the descending stack is translated into a force for raising the ascending stack and production of the conveyor assembly is economically and speedily carried out because the same consists of a minimum number of readily synchronized components.

Another important object of the invention is the provision of stationary cam structure disposed beneath the descending stack so that, after release of the lowermost unit of the lowered stack, the same will gravitate against the cam structure and be shifted thereby into the sweep of the rotatable cam element.

Pilfering of products from coin-operated vending machines is a problem which must be considered in constructing such machines. Therefore, it is a very important aim of the instant invention to provide pusher structure for transferring the uppermost tray of the raised stack onto the lowered stack including a member for blocking an open end of the tray whereby products are vended from the top of the stacks for conservation of headspace and yet access to trays in the other stack is precluded.

In its broadest sense, the purpose of the present invention is to provide a practical and dependable stacked unit conveyor apparatus comprising a minimum number of individual components and requiring minimal power for operation so that construction and operational expenses are lower than has been possible in the past.

Other objects and advantages of the present invention will become apparent from the following specification and accompanying drawings, wherein:

FIGURE 1 is a side elevational view, partially in cross-section with certain parts being broken away for increased clarity, illustrating the standby position of a stacked unit conveyor mechanism embodying the concepts and principles of the instant invention;

FIG. 2 is an enlarged, fragmentary, side elevational view of the mechanism shown in FIG. 1 with the sidewall removed;

FIG. 3 is an enlarged, fragmentary view similar to FIG. 2, showing the mechanism after having been moved through a portion of the cycle of operation;

FIG. 4 is an enlarged, fragmentary, side elevational view, similar to FIGS. 2 and 3, with the mechanism at still another position during its cycle of operation;

FIG. 5 is an enlarged, cross-sectional, elevational view taken along line 5—5 of FIG. 1;

FIG. 6 is an enlarged, cross-sectional, elevational view taken along line 6—6 of FIG. 1;

FIG. 7 is an enlarged, cross-sectional plan view taken along line 7—7 of FIG. 1;

FIG. 8 is a cross-sectional, detail plan view taken along line 8—8 of FIG. 1; and

FIG. 9 is an enlarged, cross-sectional elevational view of one end of an individual compartment.

The numeral 10 denotes a stacked compartment conveyor apparatus embodying the principles and concepts of the instant invention. Apparatus 10 includes a plurality of individual units 12 in the nature of a product compartment or tray. Each compartment 12, as best shown in FIG. 5, is transversely C-shaped and has a bottom wall 14, a pair of opposed, vertical sidewall 16, and a horizontal flange 18 extending inwardly from the uppermost extremity of each wall 16. The right and left ends of each compartment 12, viewing FIG. 1, are open, and an annular flange 20 extending outwardly from each wall 16 mounts an annular cam follower 22 of resilient plastic material such as Teflon or the like.

Trays 12, as described herein, are suitable for use with irregularly-shaped articles such as, for example, ice cream bars or packages of nuts, or with pressure deformable articles such as exemplified by pieces of pie or sandwiches since, as can be seen in FIG. 1, the bottom wall 14 of compartment 12 rests on the flanges 18 of the next lower compartment 12 and is supported thereby. It is to be understood that the specific form chosen for unit 12 is not critical, and it will be apparent to those skilled in the art that other types of trays, compartments or units may be used without deviating from the inventive concepts described herein. In this respect, it is to be noted that so long as units 12 are capable of supporting one another in a horizontal stack, they will serve the purposes of the instant invention.

Apparatus 10 has a bottom wall 23, a pair of opposed sidewalls 24 and 26, and a central wall 28 extending laterally therebetween. An inwardly directed lip 30 extends around the periphery of each wall 24 and 26, as can best be seen viewing FIGS. 6 and 7. Compartments 12 of apparatus 10 are maintained in a pair of separate, upright, side-by-side stacks 32 and 34 by the engagement of wall 28 and one end of compartment 12, and by the engagement between lip 30 and followers 22 as can be seen in FIG. 1.

It is to be noted that the individual compartments 12 in each stack 32 and 34 are supported by the other compartments 12 therebelow, and are vertically shiftable within the confines presented by wall 28 and lips 30. Thus, walls 23, 24, 26 and 28, and lips 30 present guide means for maintaining the individual compartments 12 within a horizontal, closed loop path of travel. A slot 36 is provided in lip 30 at the upper left-hand corner of walls 24 and 26 for removal and insertion of individual trays.

Apparatus 10 includes mechanism broadly designated by the numeral 38 for raising stack 32 on step, lowering stack 34 one step, transferring the uppermost unit 12 of stack 32 onto stack 34 after stack 32 has been raised one step, and transferring the lowermost unit 12 of stack 34 underneath stack 32 after stack 34 has been lowered one step. Mechanism 38 includes drive means 40 having a motor-driven pinion 42 for motivating an endless chain 44. Chain 44 is looped around a driven pinion 46 rotatable with a shaft 48 extending laterally between walls 24 and 26 at the lower ends thereof. Driven pinion 46 is shown only in FIGS. 5 and 7 and has been deleted from the other figures for increased clarity. However, it is to be understood that whenever drive means 40 is actuated, pinion 46, and thereby shaft 48, will be rotated about an axis between stacks 32 and 34.

A reciprocable pusher 50 is disposed at the upper end of apparatus 10 for transferring successive uppermost compartments 12 of stack 32 onto stack 34. Pusher 50 is mounted between a pair of elongated arms 52, each of the latter extending upwardly adjacent the outer side of a respective wall 24 or 26, and being actuated by a respective cam 54 rotatable with shaft 48 at opposite ends of the latter. The arms 52 and cams 54 on opposite sides of apparatus 10 are substantially mirror images and, therefore, only those on one side, as shown in FIG. 1, will be described in detail. Arm 52 is pivotally mounted on apparatus 10 by means 56 for swinging about a horizontal axis. Arm 52 includes a substantially triangularly-shaped plate 58 at the lower end thereof having a pair of opposed shoulders 60 and 62 extending laterally and outwardly therefrom. Cam 54 has a finger 64 engageable with shoulders 60 and 62 respectively, as cam 54 is rotated with shaft 48 for shifting plate 58 to the right and then to the left. Shaft 48 is received within an arcuate slot 66 in plate 58, permitting the latter to reciprocate as finger 64 sequentially engages shoulders 60 and 62 during the rotation of shaft 48.

Means for releasing individual lowermost compartments 12 of stack 34 for gravitation from the latter in the nature of a releasable latch 68, is pivotally mounted on apparatus 10 for rotation about a horizontal axis. Latch 68 has a shoulder 70 thereon disposed for engaging the lower right-hand corner of the lowermost compartment 12 in stack 34. Latch 68 is urged in a clockwise direction, viewing FIG. 1, by yieldable means 72 and into a position with shoulder 70 underlying stack 34. Means for selectively moving latch 68 in the nature of a bar 74 is pivotally mounted on latch 68 as can be seen in FIG. 1, and extends therefrom toward shaft 48. An elongated slot 76 in bar 74 extends longitudinally of the latter and receives shaft 48 therethrough. Slot 76 is disposed to permit bar 74 to reciprocate along its length relative to shaft 48. Triangular plate 58 has a corner 78 disposed for engaging a tab 80 extending laterally from bar 74. Thus, as plate 58 and arm 52 are moved in a clockwise direction around pivot means 56 by the interaction between finger 64 and shoulder 60, corner 78 engages tab 80 to move bar 74 rightwardly and thus swing latch 68 in a counter-clockwise direction to move shoulder 70 from beneath the lowermost unit 12 of stack 34.

Viewing FIG. 2, means in the nature of an inclined ramp 82 is disposed within the path of travel of an uppermost compartment 12 as the latter is transferred from stack 32 onto stack 34 by pusher 50. Ramp 82 is inclined upwardly and away from stack 32, thus elevating the leading edge of the uppermost compartment 12 being transferred by pusher 50 for raising the same into clearing relationship with respect to stack 34. As mentioned previously, the right-hand and left-hand ends of each compartment 12 are open. This construction is desirable for facilitating loading of the apparatus with products to be dispensed and removal of the same during the dispensing operation. Pusher 50, as can be seen in FIG. 6, includes means in the nature of a gate 84, for closing the proximal

end of the tray being shifted thereby during the transferring operation and thereafter, during standby in the position shown in FIG. 1. As mentioned previously, apparatus 10 is preferably utilized in a manner to conserve headroom and the dispensing operation is, therefore, conducted by providing access to the uppermost compartment of stack 34 immediately after transfer of the latter from stack 32 and while apparatus 10 is in its standby position. Thus, gate 84 is disposed to prevent access to the uppermost compartment of stack 32 to preclude pilfering of articles therefrom.

It is to be noted that each compartment 12 has a pair of openings 86 in each wall 16 thereof. A corresponding opening 88 is provided in wall 24, permitting an unrestricted view along the dashed line 90 shown in FIG. 8 across compartment 12. Electric eye means 92 are disposed for directing and sensing a beam of light traveling along path 90, and it can be seen that an article disposed within compartment 12 would block path 90. Thus, electrical signals emitted by electric eye means 92 may be used for controlling the operation of apparatus 10 in a manner well known to those skilled in the art.

Support means 94, pivotally mounted on apparatus 10 for rotation about a horizontal axis as illustrated in FIG. 2, has a ledge 96 and an inclined surface 98 extending transversely across apparatus 10 at the lower end of stack 32. A spring 100 is provided for yieldably biasing means 94 into a position with ledge 96 underlying the lower left-hand corner of the lowermost compartment 12 in stack 32.

Means within the path of gravitation of a compartment 12 released by latch 68 in the nature of a pair of triangular plates 102, is provided for engaging a gravitating compartment 12 and shifting the same toward stack 32. Plates 102 are disposed on opposite sides of stack 34 adjacent the inner side of walls 24 and 26, respectively, and have surfaces 104 inclined downwardly toward stack 32 and positioned for engaging the followers 22 on opposite sides of the released compartment 12. An inclined ramp 106 extends upwardly and leftwardly at the left-hand side of bottom wall 23 for a purpose to be described herein-after.

Central wall 28 terminates at its lower end in spaced relationship with respect to bottom wall 23 and adjacent shaft 48. The lower portion 108 of central wall is narrower than the remainder of the wall 28 defining a space 110 between portion 108 and respective sidewalls 24 and 27. A respective cam element 112 is mounted on each end of shaft 48 for rotation therewith adjacent the inner side of a respective wall 24 or 26 through spaces 110. Cam elements 112 on each end of shaft 48 are substantially identical—hence only one of the same need be described in detail.

Element 112 has a continuous cam track 114 on the outer periphery thereof including an arcuate surface 116 concentric with shaft 48 and a flat surface 118. In the configuration illustrated in FIG. 4, surface 118 has a portion 120 on the left-hand side of shaft 48, and a portion 122 on the right-hand side of shaft 48. Drive means 40 is operably connected with pinion 46 for driving shaft 48 and thereby element 112, in a clockwise direction viewing FIG. 4, and thus, during rotation of element 112 portion 120 is disposed for upward movement, while portion 122 thereof is disposed for downward movement. It is to be understood that the respective elements 112 on each end of shaft 48 cooperate with the latter to present structure for engaging followers 22 on each side of stacks 32 and 34.

Operation

As mentioned above, FIG. 1, along with FIGS. 2, 5, 6 and 7, illustrate the apparatus in its standby position. Viewing FIG. 2, it can be seen that a compartment 12 has been previously released by latch means 68 and has gravitated into a position underlying stacks 32 and 34 on bottom wall 23. It is to be noted that surface 116 of ele-

ment 112 is in engagement with follower 22 of the lowermost compartment 12 of stack 34 and thereby supports stack 34. Likewise, followers 22 of the lowermost compartment 12 of stack 32 engage surface 116 and are supported thereby. As elements 112 are rotated in a clockwise direction, portion 120 will move into a position engaging the followers 22 of compartment 12 resting on wall 23. At approximately the same time, surface 116 will have been rotated beyond the followers 22 of compartment 12 at the lower end of stack 32, permitting stack 32 to gravitate onto and be supported by ledge 96 of support means 94. In the meantime, upon rotation of shaft 48, finger 64 of cam 54 has been rotated out of engagement with shoulder 60 and into engagement with shoulder 62, thus urging pusher means 50 leftwardly. This action of cam 54 also results in withdrawing corner 78 from engagement with tab 80, permitting spring means 72 to bias latch 68 into a position with shoulder 70 underlying stack 34.

Upon further clockwise rotation of element 112, compartment 12 lying on wall 23 is swept laterally toward stack 32 by portion 120 of element 112 and upon contacting ramp 106, the compartment being transferred by portion 120 is elevated slightly, permitting portion 120 to move slightly beneath the follower 22 thereon, thus sweeping the compartment 12 being transferred upwardly toward stack 32. This action is best illustrated in FIG. 3, and it can be seen therein that the compartment 12 being swept upwardly will contact surface 98, forcing support means 94 against the bias of spring 100, thus permitting passage of the compartment 12 being swept upwardly, toward stack 32. Upon continued movement of element 112 in a clockwise direction, it can be seen, viewing FIG. 4, that the compartments 12 in stack 32 will be moved upwardly by portion 120 of surface 118. Likewise, in the meantime, surface 116 has rotated beyond followers 22 on the lowermost compartment 12 of stack 34. Thus, stack 34 is permitted to move downwardly in contact with portion 122 of surface 118. It can be seen, viewing FIG. 4, that the gravitational load G exerted downwardly on portion 122 by stack 34 during the downward movement of the stack, is translated about the fulcrum provided by shaft 48 into an upwardly directed force F acting through portion 120 onto the upwardly moving stack 32. Thus, the downward movement of stack 34 assists drive means 40 in raising stack 32.

Again viewing FIG. 4, upon continued clockwise rotation of element 112, stack 34 will be lowered into a position with the lowermost compartment 12 therein occupying the position designated by dashed lines and stack 34 is supported by shoulder 70 of latch 68. Also, at this point, the lowermost compartment 12 of stack 32 will have been moved upwardly beyond ledge 96, permitting support means 94 to move underneath stack 32 under the influence of spring 100. Continued clockwise rotation of element 112 will move surface 116 into a position underlying the followers 22 of the next to lowermost compartment designated 12a in stack 34.

During the movement of surface 116 into a position underlying the follower 22 of compartment 12a, cam 54 has rotated away from shoulder 62 and back into contact with shoulder 60, thereby urging pusher 50 and triangular plate 58 rightwardly, thus moving the uppermost compartment of stack 32 occupying the position shown by dashed lines in FIG. 4, rightwardly over ramp 82 and onto stack 34. As pusher 50 reaches the end of its path of travel in blocking relationship to the open end of the transferred compartment 12, now at the uppermost end of stack 34, corner 78 engages tab 80, swinging latch means 68 and shoulder 70 into a clearing position with respect to the lowermost compartment 12 of stack 34, then releasing the latter for gravitation. It is to be remembered at this point that element 112 has reassumed the position in FIG. 2; therefore, stack 34 is supported by surface 116 while the lowermost compartment gravitates therefrom.

During gravitation of the released compartment 12, the followers 22 thereof engage surfaces 104 of plates 102, and the released compartment is shifted by inclined surfaces 104 toward stack 32 and into the path of portion 120 as the latter is rotated.

Thus, it can be seen that the motor required for raising stack 32 may be of minimal size because of the counter-balancing or teeter-totter effect of surface 118. Additionally, all of the other objects, aims and purposes of the instant invention have been fulfilled in a substantial sense. It is of particular note that all of the component of apparatus 10 are operated from the single drive shaft 48 and thus, a high degree of compactness has been achieved. Furthermore, all of the various steps of apparatus 10 are caused to occur by positive actuation under the influence of cams 54 and elements 112 rotating on a common shaft 48 and, therefore, a high degree of synchronization has been achieved with a minimum number of relatively movable components.

Having thus described the invention, what is claimed 20 as new and desired to be secured by Letters Patent is:

1. In a machine having a pair of separate stacks of individual, vertically shiftable rectangular units and mechanism for raising one of the stacks one step, lowering the other stack one step, transferring the uppermost 25 unit of said one stack onto said other stack after the one stack has been raised one step and transferring the lowermost unit of said other stack underneath said one stack after said other stack has been lowered one step, said mechanism including:

movable structure engageable with the lowermost units of the stacks for simultaneously supporting both stacks during raising of said one and lowering of said other stack, 30 said structure being movable during stack raising and lowering operation about an axis disposed to translate the gravitational load of said other stack into an upwardly directed force acting on said one stack.

2. The invention of claim 1, 35 said structure including an element having a stack supporting surface, said element being rotatable about said axis, said surface being disposed relative to said axis for upward movement of one portion thereof on one side of the axis and downward movement of another portion thereof on the other side of said axis during said operation, said one portion supporting the one stack and said other portion supporting the other stack during said operation.

3. The invention of claim 2, 50 said element having a second surface movable after said operation and during continued rotation of said element, to a position supporting said other stack during said transfer of the lowermost unit of said other stack.

4. In a machine having a pair of separate stacks of individual, vertically shiftable units and mechanism for raising one of the stacks one step, lowering the other stack one step, transferring the uppermost unit of said one stack onto said other stack after the one stack has been raised one step and transferring the lowermost unit of said other stack underneath said one stack after said other stack has been lowered one step, said mechanism including:

a pusher reciprocable at the upper end of said one stack, transversely thereof and engageable with the uppermost unit of said one stack for transferring successive uppermost units of the one stack to the other stack, each of said units including a tray having an open end, 70 said pusher having means located in blocking relationship to said end of the tray being transferred thereby during transfer and until retraction of the pusher for the next succeeding transfer cycle.

5. The invention of claim 4,

and means within the path of travel of the tray being transferred by the pusher for raising the same into clearing relationship to said other stack upon which it is deposited by the pusher.

5 6. In a machine having a pair of separate stacks of individual, vertically shiftable units and mechanism for raising one of the stacks one step, lowering the other stack one step, transferring the uppermost unit of said one stack onto said other stack after the one stack has been raised one step and transferring the lowermost unit of said other stack underneath said one stack after said other stack has been lowered one step, said mechanism including:

means for releasing said lowermost unit of said other stack for gravitation therefrom only after said other stack has been lowered one step; and cam structure engageable with the released unit for moving the latter laterally and thence upwardly into engagement with the lowermost unit of said one stack.

7. The invention of claim 6, and means within the path of gravitation of the released unit for effecting lateral movement thereof prior to its continued lateral movement by said structure.

8. The invention of claim 6, 30 said structure having a unit engaging surface disposed to sweep the released unit laterally and upwardly; and means within the path of gravitation of the released unit for shifting the same during gravitation into the path of travel of said surface.

9. The invention of claim 6, 35 said structure including an element having a first surface movable to a position supporting said other stack prior to release and transfer of said lowermost unit and a second surface disposed to sweep the released unit laterally and upwardly.

10. In a machine having a pair of separate stacks of individual, vertically shiftable units and mechanism for raising one of the stacks one step, lowering the other stack one step, transferring the uppermost unit of said one stack onto said other stack after the one stack has been raised one step and transferring the lowermost unit of said other stack underneath said one stack after said other stack has been lowered one step, said mechanism including:

a releasable latch disposed for engaging the lowermost unit of said other stack after the latter has been lowered one step for supporting said other stack; means for selectively moving said latch to a position clearing said other stack after the latter has been lowered one step thereby releasing said lowermost unit of the other stack for gravitation therefrom; and structure including an element rotatable about an axis between said stacks and having a first surface movable during rotation of the element to a position supporting said other stack prior to release and transfer of the lowermost unit of said other stack and a second surface having one portion disposed to sweep the released unit laterally and upwardly toward said one stack upon continued rotation of said element, said one portion being movable during further rotation of said element to a position supporting said one stack,

55 said second surface having another portion disposed for supporting said other stack while the one portion is supporting the one stack, said second surface being disposed relative to said axis for upward movement of said one portion on one side of said axis and downward movement of said another portion on the other side of said axis upon continued rotation of the element, whereby said one stack is raised one step and said other stack is simultaneously lowered one step.

11. The invention of claim 10,

said first surface being arcuate and substantially concentric with said axis, said second surface being substantially flat, said surfaces being interconnected and presenting a continuous cam track.

12. The invention of claim 11,

each of said units including a tray having a bottom wall and a pair of side walls, there being a cam follower extending laterally from each side wall, said structure including an elongated shaft rotatable about said axis, there being one of said elements at each end thereof, said lowermost trays being disposed between said elements with the followers thereof normally engaging said track.

13. The invention of claim 10,

a pusher reciprocable at the upper end of said one stack, transversely thereof for transferring successive uppermost units of the one stack onto the other stack; and mechanism operably coupled with the pusher, the means for selectively moving the latch and said structure for operating the same in sequential synchronization.

14. The invention of claim 12,

and means below said other stack having a pair of spaced surfaces inclined downwardly toward the one stack and disposed for engaging the followers of the released tray to thereby shift the follower of the released tray during gravitation of the latter into the path of travel of said one portion.

15. The invention of claim 12,

and guide means including a pair of spaced-apart walls on opposite sides of said stacks for maintaining said trays in said stacks, each wall having inturned flange means disposed for engagement with said followers throughout the upward and downward movement of each tray.

5

10

16. The invention of claim 15, and a floor between said walls beneath said stacks, said floor and said flanges defining a closed loop path of travel for upward and downward movement and transfer of said trays.

17. In a machine having a pair of separate stacks of individual, vertical shiftable rectangular units and mechanism for shifting the upper unit of one stack onto the top of the other stack in conjunction with transfer of the lower unit of said other stack to the bottom of said one stack, the combination with said mechanism of structure for raising said one stack while lowering the other stack comprising:

a device engageable with the lowermost units of the stacks for simultaneously supporting both stacks while raising said one and lowering said other stack; means supporting said device for rotation about an axis to effect translation of the gravitational load of said other stack into an upwardly directed force acting on said one stack; and drive means connected to said device for rotating the latter.
